UNITED STATES PATENT OFFICE.

JAMES M. CONNER, OF NEW YORK, N. Y.

DESIGN FOR A FONT OF PRINTING-TYPE.

SPECIFICATION forming part of Design No. 15,966, dated March 10, 1885.

Application filed February 6, 1885. Term of patent 7 years.

To all whom it may concern:

Be it known that I, JAMES M. CONNER, of the city, county, and State of New York, have invented and produced a new Design for a 5 Font of Printing-Type, of which the following is a specification.

The nature of my design is clearly shown in the accompanying typographic impression, to which reference is made; and it consists of 10 a letter the upper and lower terminations of which are curved or concaved, and heavier than the up-and-down or vertical portions of the letters.

The character of the design is preserved in the symbol & and dollar-mark, the numerals, 15 the lower-case, and the punctuation-marks.

I claim as new--

The design for a font of printing-type, substantially as shown and described.

JAMES M. CONNER.
